2 Claims. (Cl. 178—7.1)

In my earlier application, Ser. No. 65,399, filed Feb. 24, 1936, there is described a circuit which, following on condenser-coupled low-frequency amplifiers, ensures that the potential peaks are always adjusted to an equal, absolute voltage. In the circuit set forth therein the negative peak values were in this way maintained at a certain level. In the case of direct connection with the control grid of cathode ray tubes, or upon the modulation of a transmitter from the bottom towards the top, these negative values of the amplifier output potential correspond with the black in the image (black control). The feature of the invention consisted in the use of a diode connected as a peak-voltage meter for the purpose of solving the problem.

Fig. 1 shows one form of my invention applied to the output circuit of an amplifier.

Fig. 2 shows the defect in the amplitude oscillogram and the correction desired.

Figs. 3 to 6 illustrate alternative forms of my invention.

By applying this diode 10 to the output circuit of the amplifier in accordance with Fig. 1 it is possible not only to solve the problem of maintaining the negative peaks at a constant level, but beyond this to supply a freely selective bias by way of the lead 1 to the consuming apparatus 2, for example the wireless transmitter. In Fig. 1 in accordance with the invention the bias passes from the battery 3 by way of the leak resistance 4 to the connecting lead 5, which is traversed by the total of bias and alternating potential. The valve 6 is the final tube of the image amplifier, and is coupled by condenser 7 with the preliminary stage 16. The bias is impressed at the grid of tube 6 by a battery 8 through resistance 11.

In practical operations making use of this circuit it is found that the load represented by the consuming apparatus 2 prevents exact adjustment of the peak potentials to the desired value and imparts a laxity to the level-maintaining means.

In Fig. 2 there is shown the curve *a* which an amplitude oscillogram should have in the case of a level-maintaining means acting in ideal fashion. The potential of the battery 3 is plotted as a certain positive value with the same figure in relation to the earth potential zero. The negative synchronisation impulses 8 should always reach with their peaks the line 3. If there is a load 2 present, its leakage current causes a discharge of the condenser 9, the electrode of which connected with 2 thus suffers a

loss of positive bias. The rectifying charge subsequently supplied by the diode 10 occurs in itself merely for such time as the potential of lead 5 drops at times below the potential of lead 1. This is the case, however, only during the transmission of black points of the image. Frequently the synchronisation impulse *i* is the only substantially negative part of the curve, and in the case of a load 2 it is not sufficient to cover the potential loss which occurs during a period. In consequence the curve *a* in Fig. 2 passes into the curve *b*, corresponding to a potential slip *d*. Maintenance to the desired level 3 has been unsuccessful. In this way interferences in the synchronisation may occur, and grey parts of the image may become deep black.

As a remedy against the slip in amplitude there are set forth the following three methods in accordance with the invention:

1. To furnish the diode with a higher alternating potential.
2. To bias the diode.
3. To place the diode in a grid circuit where it is not loaded.

Fig. 3 illustrates the first method. If there is passed to the consuming apparatus 2 by way of a condenser 9 merely a fraction of the oscillation potential, which has been adjusted at a tapping 12 of the anode resistance of the final valve 6, and if the diode 10 is coupled by way of a condenser 13 with the full oscillation potential of the final stage, the diode produces in idle no-load-work at the leak resistance 4 a potential which is equal and opposite to the negative peak value of the oscillations amplitude. If the diode is now connected by way of the resistance 14 with the modulation lead 5 and by way of the lead 1 with the bias 3, the said slip in amplitude by reason of the load at 2 is compensated by the over-excitation of 10.

The second method is explained in Fig. 4. It avoids the waste of oscillation amplitude involved by the method above described. In Fig. 4, there is connected in series to the diode an auxiliary battery 15, by means of which the initiation of the electronic current in 10 is advanced. By adjustment of 15 the slip in amplitude may be exactly compensated. The circuit is naturally also capable of being used in the case of mains connections.

The third method of solving the problem which is to be particularly recommended consists in removing the diode 10 entirely from all loaded circuits and disposing the same in the grid circuits of the power amplifier. Two schemes of this

kind are shown in Figs. 5 and 6. In Fig. 5 there is shown a preliminary amplifier tube 16, which is coupled by way of a condenser 7 in R-C connection with the grid of the final tube 6. In this case the valve 6 must be provided with a special insulated potential source 18 for grid and anode. Since the sign of an oscillation, which is negative in the anode circuit, is positive in the grid circuit, the polarity of the diode 10 must also be changed, and it is connected by the anode with the control grid of 6, and in parallel to its leak resistance 11. The tube 10 operates without error in this form, even without over-excitation or auxiliary bias, so long as the tube is not traversed by grid currents. This must be ensured by means of a sufficiently large grid bias 18. The cathode of the tube 6 is earthed by way of a condenser 19.

Fig. 6 shows a circuit in which the bias necessary for maintaining a constant level is also taken from the grid circuit of the amplifier 6, but in which this bias itself is not conjointly amplified in the tube 6 but is employed in direct fashion. The circuit, therefore, possesses certain disadvantages as compared with Fig. 5. The diode 10 is connected but in series with condensers 22 and 20, and accordingly loads the grid circuit of 6 but to very little extent. The anode of 6 is connected to the consuming apparatus 2 by way of a condenser 9 and lead 5. The regulating bias is received by this consuming apparatus from a condenser 20 through the medium of a leak resistance 21. The condenser 20 is positively charged by the tube 10, as it is connected with its cathode. The anode of the tube is connected by way of a condenser 22 with the anode of the preliminary valve 16. The bias is only equal to the maximum output potential of 6 when the amplification of 6 is equal to 1:1, as the excitation of 10 takes place only with the grid alternating potential of 6. The tube 10 is bridged by a leakage 23, whilst the desired bias 3 is supplied by way of a resistance 24. Immediately the condenser 20 has been charged to a positive bias, which is equal to the maximum positive potential of the grid of 6, all flow of current to the condenser 22 ceases, and a loading of 16 by the regulating elements no longer takes place. A possible slip may be compensated also in this case by the use of over-excitation or auxiliary potential. An independent compensation of the slip, however, occurs automatically in this case owing to the fact that the leak current flowing to the consuming apparatus 2 by way of the resistance 23 biases itself. The drop in potential at 23 biases the anode of 10 positively in relation to the cathode and facilitates or advances the initiation of the emission.

Finally it may be mentioned that the devices

set forth in the above, which are employed here for maintaining the negative peak values at a constant level, may also be employed without difficulty for maintaining constant peak values of positive sign merely by changing the polarity of the two-electrode tube 10. This may be necessary in all transmission methods in which modulation is performed in reversed fashion, i. e., with increasing aerial current upon decreasing light intensity. In Fig. 5 there is shown a reverse-polarity connection of this kind rendered necessary by the fact that the reversed polarity has required to be considered within an amplifying stage. Generally speaking, the slip errors are considerably greater when maintaining positive peak values, as in all of these cases the bias of the modulating line 5 requires to be raised to a high positive potential and the leak currents are correspondingly greater. Upon connecting the diodes in the grid circuits in accordance with Fig. 5 these difficulties are overcome without trouble.

It may be specifically remarked that in the above there have been described merely particular forms of embodiment of the general idea according to the invention, and that the stated measures may be employed both in combination as well as singly.

I claim:

1. In a television apparatus comprising an amplifier tube the grid of which is supplied with the mixed image and synchronisation signals and the alternating anode potential of which is conducted to the input of a consuming apparatus, a device for maintaining constant the potential level of said input independently of the consumption of said apparatus, said device consisting of a diode shunting the grid leak of said amplifier tube thus producing a bias equal to the amplitude of said alternating potential.

2. In a television apparatus comprising an amplifier tube the grid of which is supplied with the mixed image and synchronisation signals and the alternating anode potential of which is conducted to the input of a consuming apparatus, a device for maintaining constant the potential level of said input independently of the consumption of said apparatus, said device consisting of a diode which is connected on one side via a condenser to said grid and via a resistance and a bias source to earth, and on the other side via a resistance to said input and via a condenser to earth, and which is shunted by a high resistance, said amplifier having an amplification factor of about 1 so that the bias produced by said anode is equal to the amplitude of said alternating potential.
